STRIP UNCOILER GRADING

Ambrose J. Wardle, Youngstown, Ohio, assignor to The McKay Machine Company, Youngstown, Ohio, a corporation of Ohio

Application November 28, 1936, Serial No. 113,263

16 Claims. (Cl. 242—78)

This invention relates to a machine for uncoiling metal strip and more particularly to a machine for such purpose which is dependable in its operation and which effectively performs its function without injury to the material being handled.

10 It is common industrial practice to wind the metal strip into compact coils by means of reels as it issues from the rolling mill or other processing equipment to aid in handling and shipping the same. Before being coiled, the strip is coated with a thin film of oil to prevent premature corrosion, thus preserving the smooth surface attained by modern manufacturing methods. Fabricators and other users of metal strip provide their plants with apparatus to uncoil the strip as received in coil form and some plants have installations for the automatic and continuous production of pressed steel products wherein a

15 device for intermittently feeding lengths of strip to the press or stamping machine is positioned between the uncoiler and the press or stamping machine. To insure a high rate of production the uncoiler must necessarily deliver an unfailing supply of uniform strip. The rate of delivery being controlled in accordance with the demands of the feeding mechanism.

20

Accordingly, it is an object of the invention to provide a strip uncoiler cradle on which the coil may be easily placed and held in position by gravity and in which novel guide means is employed which guide means is operative to perform its function without danger of injury to the side edges of the strip being uncoiled.

35 Another object of the invention is to provide improved means to support and rotate the coil to aid in keeping the coil on the cradle and to insure sufficient rotation of the coil that it may deliver an adequate supply of strip.

40 A further object of the invention is to provide improved means to control the delivery of strip from the coil in accordance with the demand of feeding or other mechanisms, the control means being contained entirely in the uncoiling machine whereby the uncoiling machine may be used in conjunction with feeding mechanisms without modification thereof and without the need of any electrical or mechanical connection between the uncoiler and the feeding device except the metal strip itself.

45

50

Other objects and advantages of the invention will become apparent from a consideration of the drawings and the following detailed description wherein selected embodiments of the invention are disclosed.

In the drawings:

Figure 1 is a side elevation of a metal strip unroller constructed in accordance with my invention:

Figure 2 is a cross-sectional view of the uncoller taken along the line 2-2 of Figure 4, looking in the direction of the arrows:

Figure 3 is a cross-sectional view of a coil supporting roll:

Figure 4 is an end elevation of the uncoiler; 10

Figure 5 is a cross-sectional view taken along the line 5-5 of Figure 1, showing the coil in position and diagrammatically illustrating the controlling circuit;

Figure 6 is a partial plan view of the coil supporting cradles; and 15

Figure 7 is an elevation of a modified form of apparatus embodying my invention.

Referring to the embodiment of the invention illustrated in Figures 1 to 6, inclusive, the numeral 10 designates the hollow supporting base for the apparatus which is preferably constructed by welding together suitably formed plates and sections. One end of the base is provided with a raised portion 11 to form a raised support for a slideable guide carrier 12. Suitably secured to the base 10 at its other end is a pedestal 13 to form a raised support for another guide carrier 15. The raised portion 11 of the base 10 and the pedestal 13 also form the end supports for a cradle assembly adapted to receive and rotatably support a coil 14.

The cradle assembly is supported by a pair of spaced parallel shafts 16 having their ends journaled in the side walls of the base portion 11 and the pedestal 13. As shown more clearly in Figures 5 and 6, a cradle 17 consisting of a rigid rectangular frame is rotatably supported on each of the shafts 16 which pass through the centers of the end members 18 of the cradles 17. If desired, suitable anti-friction bearings may be provided between the shafts 16 and end members 18 to eliminate the tendency of the rotation of the shafts to rotate the cradles and to prevent the cradles from moving longitudinally along the shafts. Each of the cradles is provided with a pair of shafts 19 parallel to and equally spaced from the shaft 16 and having their ends rotatably supported in the end members 18. A roll 20 is securely keyed to each of the shafts 19 in lateral alignment with each other to form spaced supports for the coil 14.

A spur gear 21 is keyed to the shaft 16 within the cradle frame 17 adjacent to the end member 18 and meshes with gears 22 keyed to the roll 15.

carrying shafts 19, the gears 22 being laterally aligned with respect to gear 21. It can therefore be readily seen that rotation of the shafts 16 results in rotation of the coil supporting rolls 20 and the consequent rotation of the coil supported thereon. Since the cradle frames 17 are free to rotate about the axes of the shafts 16, each of the four rolls 20 will be in constant engagement with the outer surface of the coil 14 regardless of its 10 diameter. I have found this feature to be of distinct advantage as it materially reduces the danger of the coil being pulled off the uncoiling machine by the action of the pinch rolls 30, Figure 5, or other feeding mechanism with which 15 the uncoiler may be used.

As shown more clearly in Figure 3, the coil supporting rolls 20 consist of a metallic hub 24 tired with a thick layer of rubber 25 intimately bonded with the metal of the hub. Preferably 20 the rubber 25 is of a synthetic composition of the type resistant to the normal deleterious action of hydrocarbon compounds. This is a desirable feature since the oil coating of the strip would quickly deteriorate natural rubber if used on 25 the rolls.

The use of rubber on the rolls enhances the friction between the coil and the rolls and this together with the cradles arrangement whereby all four rolls are in constant engagement with the 30 coil results in the coil being positively rotated upon rotation of the rolls. The final result is that an adequate supply of strip is uncoiled and the tendency of the feeding mechanism with which the uncoiler may be associated to pull the 35 coil from the machine is obviated.

Motor 31 transmitting through the flexible coupling 34 and variable speed transmission 32, all housed within the base 10, is utilized to drive the shafts 16 and rolls 20. The speed of rotation 40 of the elements is controlled by operation of the handwheel 33. A transversely extending shaft 35 journaled within the pedestal 13 is coupled with the output shaft of the variable speed transmission 32 by the chain 36 and drives both the shafts 16 through worms 37 and worm 45 gears 38 housed within the pedestal.

Slidably mounted in a longitudinally extending bore 49 in the upper end of the pedestal 13 is the guide carrier 15 rotatably supporting at its 50 inner end a rotary guide generally indicated at 41 having a hub 42 mounted on the end of the carrier by the bearing assembly 43, a circular plane disk 44 and braces 45 welded to the hub and disk. The carrier 15 is longitudinally adjustable by a 55 toothed rack 46 secured thereto and meshing with a spur gear 47 carried by a transverse shaft 48 provided at its outer end with a handwheel 49. Rotation of the handwheel results in longitudinal movement of the carrier 15 and operates to bring 60 the rotary guide 41 in contact with the adjacent side edge of the coil. Bolts 50 and 51 may be employed to lock the guide in selected position.

Another rotary guide generally indicated at 60 is employed to engage the other side edge of the 65 coil and consists of a circular plane disk 61, a backup plate 62, hub 63 and braces 64 welded to the hub and backup plate. Bolts or rivets 65 encircled by spacing sleeves 66 are employed to provide a truss construction for increased strength 70 and rigidity. The guide 60 is rigidly secured to a shaft 68 rotatably mounted in a longitudinally extending bore of the carrier 12 by means of the anti-friction thrust bearings 69. The carrier 12 is slidably mounted in a dovetailed groove in the 75 top of the raised base 11 and is adjustable longi-

tudinally therein by a screw 70 threadedly engaged with an aperture in lug 71 depending from the carrier. The adjusting screw 70 is restrained from longitudinal movement by the collars 72 secured to the screw. Bolts 73 lock the guide carrier in selected position.

The rotary guides 41 and 60 keep the strip in position during the uncoiling thereof and rotate with the coil. The guides are freely mounted and operate in such a manner that should a portion 10 of an edge of the strip be forced into tight engagement with the face of the guide, the guide will be rotated and so will prevent the tearing or deformation of the edge of the strip. As explained above the rotary guides are longitudinally 15 adjustable with respect to the coil supporting rolls 20 and with each other; this in order that the device may accommodate coils of different widths and that the guides may fit closely against the side edges of the strip. 20

To control the rate of delivery of the strip from the coil I employ the switch 76 mounted adjacent the periphery of the coil and operated by the arm 77 to control the operation of the motor 31. The switch 76 is mounted on the holder 75 25 which in turn is pivotally mounted on the outer side member of a cradle 17. As the cradle 17 rotates inwardly upon reduction in diameter of the coil the switch 76 moves toward the center of the coil and thus tends to follow the inward 30 movement of the periphery of the coil. The switch is operated by the arm 77 which is provided at its outer end with a roller to engage the surface of the strip when the strip loops outwardly as at 78 as will occur when the uncoiler is 35 dispensing the strip at a greater rate than is demanded by the feeding mechanism or pinch rolls 30. The movement of switch arm 77 by the strip 40 operates to deenergize the motor 31 and stop the rotation of the coil. 40

In Figure 7 there is illustrated a modified form of the apparatus wherein the left guide member is omitted and the cradles are set in an inclined position. In this device the coil 14 is supported conjointly by the rolls 20 and the rotary guide 45 member 60. A base 80 supports the elements and the gear case 91 supports the transverse drive shaft 35, one end of the cradle supporting shafts 16 and houses the worms 37 and the worm gears 38. Aside from these changes the device is identical with the structure of Figures 1 to 6. 50

Having thus described my invention what I claim is:

1. A coil supporting and rotating assembly for a strip uncoiling device comprising a pair of spaced parallel supporting and driving shafts, means to rotatably support the ends of the shafts, a cradle rotatably supported on each of the shafts, a pair of spaced roll carrying shafts journaled in each of said cradles and being in parallel alignment with the driving shafts, a coil supporting roll carried by each of said roll carrying shafts and power transmission means between the driving shafts and each of the roll carrying shafts whereby rotation of the driving shafts results in rotation of the roll carrying shafts. 55

2. A coil supporting and rotating assembly for a strip uncoiling device comprising a pair of spaced parallel supporting and driving shafts, 70 means to rotatably support said shafts, a cradle rotatably supported on each of said shafts, a pair of spaced coil supporting rolls carried by each cradle and having their axes of rotation parallel with said shafts, and driving means between the 75

shaft and the rolls whereby rotation of the shaft results in rotation of the rolls.

3. A metal strip uncoiling device comprising a plurality of arcuately disposed supporting and 5 rotating rolls adapted to support and rotate a coil of metal strip, guide members for said coil comprising a pair of spaced parallel disks positioned above and on either side of said rolls, said disks being mounted for free rotation on longitudinally aligned bearings extending parallel to the axes of rotation of the rolls, and means to rotate said rolls.

4. A metal strip uncoiling device comprising a hollow base member having a raised portion at 15 one end, a hollow pedestal secured to said base member at its other end, a pair of spaced parallel shafts having their ends journaled in the raised portion of the base and in the pedestal, a transverse shaft in said pedestal for rotating 20 said parallel shafts, a motor in said base for rotating said transverse shaft, a cradle rotatably supported on each of said parallel shafts, a pair of coil supporting and rotating rolls journaled in each cradle for rotation on axes parallel with the 25 parallel shafts, driving means between the parallel shafts and the rolls whereby the rolls may be caused to be rotated, a guide comprising a disk positioned normal to the axes of the parallel shafts and thereabove, means including said pedestal to support said disk for rotation in the plane including the disk, a second guide comprising a disk spaced from and parallel with the first named disk, and means including said raised portion of the base to support said second mentioned 35 disk for rotation in its plane.

5. A metal strip uncoiling device comprising a base member having a raised portion at one end, a hollow pedestal secured to said base member at its other end, a pair of spaced parallel shafts, 40 having their ends journaled in the raised portion of the base and in the pedestal, a transverse shaft in said pedestal for rotating said parallel shafts, means to rotate said transverse shaft, a cradle rotatably supported on each of said parallel shafts, a pair of coil supporting and rotating rolls journaled in each cradle for rotation on axes parallel 45 with the parallel shafts, driving means between the parallel shafts and the rolls whereby the rolls may be caused to be rotated, a guide member comprising a disk positioned normal to the axes of the parallel shafts and thereabove but to one side of the rolls, and means including said raised portion to support said disk for rotation in the plane including the disk.

6. A metal strip uncoiling device comprising a plurality of arcuately disposed coil supporting rolls, means to rotate said rolls, guide members for the coil comprising a pair of spaced parallel disks positioned above and on either side of said 50 rolls, said disks being mounted for free rotation on longitudinally aligned bearings extending parallel to the axes of rotation of the rolls, and means to selectively position the guides along the longitudinal line of their axes of rotation.

7. A metal strip uncoiling device comprising a plurality of arcuately disposed coil supporting rolls, means to rotate said rolls, a rotary guide member adapted to engage a side edge of the coil comprising a disk positioned above and to one 55 side of said rolls, said disk being mounted for free rotation in a plane normal to the axes of rotation of the rolls, and means to selectively position the guide along the longitudinal line of its axis of rotation.

8. A metal strip uncoiling device comprising

a plurality of arcuately disposed coil supporting rolls, means to rotate said rolls, a rotary guide member adapted to engage a side edge of the coil comprising a disk positioned above and to one side of said rolls, said disk being mounted for free rotation in a plane normal to the axes of rotation of the rolls.

9. A strip uncoiling device comprising means to rotatably support the coil, a pair of spaced parallel rotary guide members adapted to engage opposite edges of the coil, each guide member comprising a disk positioned above and to one side of the coil supporting means, said disks being mounted for free rotation in planes parallel with the side edges of the coil. 15

10. A strip uncoiling device comprising a base, a pair of spaced parallel shafts mounted on said base in an inclined position, a cradle rotatably carried by each shaft, a pair of spaced coil supporting rolls journaled in each cradle, driving means between the shafts and the rolls whereby rotation of the shafts results in rotation of the rolls, a rotary guide comprising a disk mounted in a plane normal to the axes of the shafts and above the lower ends thereof, said disk forming a support for the coil and adapted to rotate freely upon rotation of the coil.

11. A strip uncoiling device comprising a base, a plurality of arcuately disposed coil supporting rolls arranged with their axes parallel with each other but inclined with respect to the horizontal, a rotary guide comprising a flat disk positioned at the lower end of said rolls and lying in a plane normal to the axes of rotation of the rolls, said disk forming a support for the coil and adapted to rotate freely upon rotation of the coil.

12. A strip uncoiling device comprising a base, a pair of spaced parallel shafts mounted on the base, a cradle rotatably mounted on each shaft comprising a frame having side members and end members, a pair of spaced coil supporting rolls journaled in each cradle and having their axes of rotation parallel with the shafts, a switch supported on the outer side member of a cradle and having an operating arm positioned adjacent the periphery of the coil and adapted to be actuated by a loop from the coil, and means controlled by said switch to drive the coil supporting rolls. 40 45

13. A strip uncoiling device comprising a base, a pair of cradles pivotally supported on said base, a pair of spaced parallel coil supporting rolls journaled in each cradle and having their axes of rotation parallel with the axes of rotation of the cradles, means to rotate said rolls, an arm pivotally mounted on one of said cradles positioned adjacent the periphery of the coil and adapted to be actuated by a loop from said coil, and means actuated by said arm in control of said roll rotating means. 50 55

14. A coil supporting and rotating assembly for a strip uncoiling device comprising a base, a pair of cradles rotatably supported on said base on spaced parallel axes, a pair of coil supporting roll carrying shafts rotatably mounted on parallel axes on each of said cradles, said last mentioned axes being parallel with said first mentioned axes, a coil supporting and rotating roll keyed to each of said roll carrying shafts, and means to rotate said roll carrying shafts in all positions of said cradles. 60 65 70

15. Structure according to claim 14 including a tire on each of said rolls, said tire being of a synthetic rubber composition to provide driving friction and to prevent marking of the material being uncoiled. 75

16. A metal strip uncoiling device comprising means to rotatably support a coil of strip, a guide member for said rotating coil comprising a rotary disk adapted to engage the side edge of the coil and the side edge of the material as it is being uncoiled, said disk being mounted for free rota-

tion in a plane including the disk and parallel to the side surface of the coil, and means to move said disk longitudinally with respect to said coil supporting means.

AMBROSE J. WARDLE. 5
